UNITED STATES PATENT OFFICE.

EUGENE R. WEBER, OF ROCHESTER, NEW YORK, ASSIGNOR TO SARGEANT & GREEN-LEAF INC., OF ROCHESTER, NEW YORK, A CORPORATION OF NEW YORK.

LOCK.

Application filed June 16, 1922. Serial No. 568,832.

To all whom it may concern:

Be it known that I, EUGENE R. WEBER, a citizen of the United States, residing at Rochester, in the county of Monroe and 5 State of New York, have invented certain new and useful Improvements in Locks; and I do hereby declare the following to be a full, clear, and exact description of the same, reference being had to the accompanying drawings, forming a part of this 10 specification, and to the reference numerals marked thereon.

This invention relates to locks and more particularly to the variety having a rotary 15 cylinder or plug extended through the wall portion or other supporting means to which a lock is attached to receive a key or other operating device, the chief object of the invention being the provision 20 of simple and efficient means for effectively preventing the cylinder or plug from being forcibly displaced for obtaining access to or disabling the lock. To these and other ends the invention resides in cer- 25 tain improvements and combinations of parts all as will hereinafter be more fully described, the novel features being pointed out in the claims at the end of the specification.

30 In the drawings:

Figure 1 is an exterior view of a door having a lock embodying the present invention supported on the interior side thereof;

35 Figure 2 is a sectional view on the line 2^a—2^a, of Figure 3, showing the construction for securing the cylinder or plug against displacement from the door;

Figure 3 is an elevation of the parts 40 shown in Figure 2 as appearing at the interior side of the door;

Figure 4 is a section on the line 4^a—4^a of Figure 2;

Figure 5 is a view of a door having a 45 lock applied thereto embodying a modified form of the invention;

Figure 6 is a sectional view on the line 6^a—6^a of Figure 7;

Figure 7 is a sectional view on the line 50 7^a—7^a of Figure 6 illustrating the construction shown in Figure 5 for securing the cylinder or plug against displacement.

Similar reference numerals throughout the several views indicate the same parts.

55 The invention is disclosed in the present

instance, by way of illustration, as embodied in a lock of a variety particularly adapted for use on the closure or door of a safe deposit box, the door being represented in the drawings at 10, having the 60 lock 11 secured to the interior side thereof in any suitable manner, as, for example, by screws 12. It has been found desirable to construct locks of this character with a cylinder or plug extending through an opening 13 in the door to the exterior side of the latter for rotation by a key or other operating means. Security box doors of this type are commonly constructed of steel and those desiring to forcibly open the door 70 for unauthorized purposes have heretofore found it possible in most instances to forcibly displace the lock plug, either by extracting the same at the exterior side of the door or by driving the plug inwardly 75 through the lock, thereby securing access to the lock or disabling the same and thus unlocking the door.

The present invention provides an improved construction for effectively preventing the forcible displacement of the lock plug in this manner, while at the same time interposing no interference with the normal operation of the plug, or the authorized removal of the lock from the inside of the door 80 for repair or replacement. To this end either the wall of the opening 13 in the door which receives the lock plug, indicated at 14, or else the circumferential surface of the latter, or both, have formed therein an 85 arcuate channel or groove 15 cooperating with means engaging the adjacent surface of the other member to secure the plug means against displacement while leaving it free to rotate in the opening 13. In the 90 present instance this construction is given the form of a channel or groove 15 in the circumferential surface of the plug means for cooperating with ball means or members 16 engaging in a corresponding groove 95 17 in the wall of the opening 13 of the supporting means. These opposing grooves thus form in effect a ball race which is substantially filled with the ball members 16, as shown in Figure 4, effectively locking 100 the plug means against displacement in either direction from the opening in the door. The balls 16 may be inserted, or removed, if necessary, after the plug means has been located in its opening in the door, 110

through a passage communicating with the ball race and opening exteriorly through a surface of the plug means or of the supporting means or door inaccessible from the 5 outside of the latter. In the preferred form this passage is shown at 18 as formed in the plug means itself, having one end turned angularly into communication with the ball race, and the other opening at the inside 10 of the plug and closed by any suitable means, such, for example, as the threaded stopper 19. In this case an additional ball 20 is placed in the passage to prevent the balls in the race-way from entering the latter, except when the stopper 19 is removed.

To increase the difficulty of driving the plug inwardly of the door, the plug is preferably provided with an annular shoulder 21 cooperating with a similar shoulder in 20 the sides of the opening 13. This increases the resistance of the plug to force applied to displace the same inwardly, it being more difficult to pull the plug outwardly of the door because of the difficulty of applying 25 the necessary force thereto.

While the plug means 14 described above may be constructed integrally with the cylinder or plug which extends through and operates the lock, it is preferred to form 30 the plug in sections. That is to say the plug means 14 is preferably extended to a plane 21^a spaced somewhat from the inner surface of the door, in abutting relation with the outer end of the plug 22 extending 35 through the lock, these plug sections being separably connected for conjoint rotation by any suitable device, such, for example, as the dowel pins 23 in the plug means 14 engaging in corresponding openings 24 in 40 the lock plug 22. By this arrangement the plug means 14 and the plug 22 rotate as one while the lock is in place on the door, and the lock may be readily detached if found necessary without removal of the plug 45 means or section 14. In the modification described above the parts are assembled by first placing the plug means 14 in position in opening 13 of the door and then inserting the ball members into position through 50 the passage 18, which is then closed by means of the stopper 19. When the plug means has thus been secured in position, the lock proper may be attached to the door, the plug means 14 being rotated to bring its dowel pins 23 55 into registry and engagement with the openings 24 of the lock plug 22.

Various modifications in the specific embodiment of the invention have been contemplated. Thus in Figures 5 to 7 the walls 60 of the opening 25 receiving the plug means 26 and the circumference of the latter are provided the one with a circumferential groove 27 and the other with sockets 28 for the ball members 29, the sockets in the present instance being formed in the plug

means, although, of course, this arrangement might be reversed to locate such sockets in the supporting means or door 10. The passage 30 for inserting the balls 29 in this modification is arranged to open exteriorly 70 through the end of the door, being closed by stopper 31. The plug means, as before, is connected by dowel pins 32 with the plug of the lock, the parts being so disposed and arranged that when the lock is in place, the 75 limited movement of its plug 22 correspondingly limits the rotation of the plug means 26 so that the key opening 33 moves through the small angle included by the angular line 80 b, c to prevent the ball members from becoming displaced from their sockets and entering the passage 30.

In the assembly of this modified construction the plug means 26 is located in its opening 25 in the door and the ball members inserted in their sockets through passage 30, the plug means being rotated to the proper position to receive the ball and the door being tilted so that the balls drop through the 90 passage 30 by gravity. When the lock is 95 then attached to the door with its plug 22 in engagement with plug means 26 the movement of the latter is limited in the manner described, so that none of the ball members are brought during the operation of the lock 100 sufficiently into registry of the opening to permit the displacement of the balls, Figure 7 showing one of the limiting positions of movement. While ball members have been shown in the present instance in engagement with one of the movable parts for cooperation with a groove of the other it is obvious that elements other than ball members might be employed for this purpose. The lock and plug means may of course be supported on the door frame or other stationary part 105 instead of on the door.

The invention thus provides a simple and practical construction for the lock plug or cylinder, and door or other supporting means for the lock, which effectively prevents access to or injury of the lock by the unauthorized forcible displacement of the plug either outwardly or inwardly of the door, while the lock proper may be as 115 readily assembled or detached as before.

I claim as my invention:

1. The combination of a lock provided with rotary plug means, supporting means to which the lock is attached having an opening therein in which said plug means is received, and a securing device comprising an arcuate channel on one of said means and a part engaging the other and projecting into said channel for preventing forcible displacement of the plug means.

2. The combination of a lock provided with a rotary plug, supporting means for the lock having an opening therein, auxiliary plug means rotatable in said opening, a

- separable connection between said lock plug and auxiliary plug means insuring conjoint rotation thereof, and a securing device comprising an arcuate channel on one of said means and a part engaging the other and projecting into said channel for preventing forcible displacement of the plug means.
3. The combination of a lock provided with rotary plug means, closure means to which the lock is attached having an opening therein through which said plug means is rotarily extended, and a securing device comprising a circumferential channel in the periphery of said plug means and cooperating means engaging said supporting means and projecting into said channel to permit rotation of the plug means and prevent forcible displacement thereof from said supporting means.
- 20 4. The combination of a lock provided with rotary plug means, supporting means for the lock having an opening therein through which said plug means is rotarily extended, and a securing device comprising an arcuate channel formed in one of said means and ball members carried by the other for rolling engagement with said channel to prevent forcible displacement of said plug means.
- 25 5. The combination of a lock provided with rotary plug means, supporting means for the lock having an opening therein through which said plug means is rotarily extended, and a securing device comprising opposed arcuate channels in said plug and supporting means forming a ball race and ball means in said race for preventing forcible displacement of said plug means.
- 30 6. The combination of a lock provided with rotary plug means, supporting means for the lock having an opening therein in which said plug means is received, and a securing device comprising a circumferential channel formed in one of said means, ball members engaging the other of said means for rolling engagement with said channel, and an exteriorly opening passage way in one of said members for the insertion of said ball members.
- 35 7. The combination of a lock provided with a rotary plug, supporting means for the lock having an opening therein, auxiliary plug means rotatable in said opening, a separable connection between said lock plug and auxiliary plug means insuring conjoint rotation thereof, a ball race formed by recessed portions in each of said means, and ball members in said race preventing forcible displacement of said plug means.
- 40 8. The combination of a lock provided with a rotary plug, supporting means for the lock having an opening therein provided with an annular shoulder, auxiliary plug means rotatable in said opening and having a shoulder engaging the shoulder of said supporting means to prevent movement of said plug means in one direction in said opening, a dowel pin connection between said lock plug and plug means insuring conjoint rotation thereof, a ball race comprising circumferential channels formed in said supporting means and plug means, ball members in said race preventing movement of said plug means in the other direction and a passage opening exteriorly of one of said means for insertion of said ball members.
